[57] CLAIM

The ornamental design for a torchiere lamp, as shown
and described.

DESCRIPTION

FIG. 1 is a perspective view of the torchiere lamp
showing my new design;

FIG. 2 is a front elevational view of the torchiere lamp,
the rear elevational view being identical;

FIG. 3 is a right side elevational view of the torchiere
lamp, the left side elevational view being identical;

FIG. 4 is a top plan view of the torchiere lamp; and,

FIG. 5 is a bottom plan view of the torchiere lamp.
